UNITED STATES PATENT OFFICE

2,462,397

ASH RECEIVER

Cornelius Hendricks, Grand Rapids, Mich., assignor to Applied Arts Corporation, Grand Rapids, Mich., a corporation of Michigan

Application August 28, 1944, Serial No. 551,465

3 Claims. (Cl. 45—77)

1

This invention is directed to the production of an ash receiver which in normal use is mounted upon the dash of an automobile. Ash receivers for holding ashes and other refuse from smoking when thus mounted must be easily operable and avoid undesirable rattlings and other noises liable to occur from the vibration of the automobile and this invention is directed to a very practical and economical ash receiver of a pull-out or drawer type which is quickly and easily mounted, is manufactured at low cost, may be easily moved from inner to outer position and back again to inner position, which is stopped at a predetermined outer position but may be readily released for a removal of the ash receiver for disposal of its contents, and which is not productive of rattles or other undesired noises. An understanding of the invention for the attainment of the ends stated, as well as others which will appear may be had from the following description taken in connection with the accompanying drawings, in which,

Fig. 1 is a longitudinal section substantially on the plane of line 1—1 of Fig. 4 looking in the direction indicated and showing the ash receiver at its inner retracted position.

Fig. 2 is a similar section with the ash receiver pulled out to an outer position for the reception of ashes and the like.

Fig. 3 is a rear elevation.

Fig. 4 is a plan of the ash receiver receptacle and the mounting therefor, and

Fig. 5 is a transverse vertical section on the plane of line 5—5 of Fig. 4 looking in a forward direction as indicated.

Like reference characters refer to like parts in the different figures of the drawing.

The automobile dash 1 of sheet metal has a rectangular opening 2 therethrough at which the ash receiver is mounted. The ash receiving construction includes a support made from a plate of sheet metal having an upper horizontal side 4 and downturned spaced apart sides 5. Said support is connected to the dash 1 by means of front and back angle brackets 3, the vertical legs of which are secured at the front and rear sides of the dash, the horizontal legs being provided with screw threaded openings for the passage of screws 6 upwardly through the upper side 4 of the support, the support thus permanently connected to the dash extending partly in front thereof but with the major portion to the rear as shown in Figs. 1 and 2. Spaced beveled rollers 7 are mounted upon and carried at the inner sides 5 of support. The upper side 4 thereof at its front

2 edge and midway between its side edges has a downturned lip 8 struck therefrom to serve as a stop for the movable receptacle as will later appear. At the rear of the support and toward each side spring members 9 are permanently connected at their rear ends and are bifurcated and provided with hooked portions at their front ends to fit over the axles of small rollers 10 which, at their lower portions, extend downwardly through openings cut in the upper side 4 of the support, the purpose of which will be hereinafter described.

The ash receiving member of the construction is a drawer made substantially from sheet metal. A single length of sheet metal is formed as a horizontal bottom 11 with an upwardly inclined front section 12 which is continued in a vertical front end 13. The bottom 11 is continued upwardly at the rear as a vertical end 14 and the metal is then turned to extend in a forward direction, making a horizontal section 15 lying over and spaced from the rear portion of the bottom 11. Toward its front end the section 15 is provided with an upwardly pressed stop 16 which when the drawer is pulled outwardly strikes against the stop lip 8 previously mentioned to limit the outward movement of the drawer. The drawer is completed by two sides 17 of sheet metal which have upper and lower offset portions connected by inclined sections 18 which ride upon the beveled rollers 7. The sides 17 are provided at their lower edges with inturned horizontal bottom flanges 19 coming underneath the side edges of the bottom sections 11 and 12 and secured thereto by spot welding or other suitable permanent connection. Rear end flanges 20 are also turned from the rear ends of the sides at the lower portions thereof, bearing against the back 14 and likewise permanently connected thereto in the same manner. At the front end of the drawer inturned flanges 21 lie in front of the front 13 and are welded or otherwise permanently secured.

At the upper edges of the sides of the drawers horizontal inturned flanges 22 are made which extend over the described section 15 but are not permanently secured thereto at least for the full length of the section 15, as the outer end portion of said section is free to be pressed downwardly to disengage the stop 16 from the stop 8 when the ash receptacle is to be completely removed. In said inturned flanges 22 at spaced apart front and rear positions downwardly pressed concave recesses 23 are made. The rollers 10 bear with spring pressure upon the said flanges 22 and when any recesses 23 come to said rollers they fit in the

recesses and yieldingly hold the drawer receptacle against accidental movement. For reinforcing and strengthening purposes the horizontal section 15 described may be provided with corrugated ribs 24 as shown.

At the front of the drawer an ornamental and drawer pulling front member 25 is secured by means of screws as shown, and which depends below the bottom of the drawer receptacle to be readily engaged by the fingers back of said front 25 for withdrawing the drawer ashes receptacle.

With this construction when the drawer receptacle is fully retracted, as shown in Fig. 1, the rollers 10 are seated in the front recesses 23 and, pressed upon by the springs 9, force the bearing sections 18 into firm engagement with the beveled rollers 7. The drawer receptacle may be pulled outwardly to the position shown in Fig. 2 until stopped by the engagement of stops 8 and 16 as shown. This leaves a projecting portion of the drawer open at its upper side and at its front, so that ashes and other refuse may be placed therein. The rollers 10 bear with yielding pressure against the flanges 22 at all times and enter the rearmost recess at 23 when the drawer is fully extended, preventing any accidental or aimless movements thereof. When the drawer is to be entirely removed a downward pressure is exerted upon the front end portion of the section 15 to press the stop 16 below the stop 8, whereupon the drawer may be removed and a disposal made of its contents, after which it may be returned to place.

The construction is practical, economical, very effective and attractive in appearance and eliminates undesirable rattlings and other noises. Being under spring pressure and with the downwardly and inwardly inclined sections 18 bearing against the beveled rollers 7 the drawer is centered and all movements are substantially noiseless. Furthermore the force required to move the drawer is slight. The construction has proved very practical in service.

The invention is defined in the appended claims

and is to be considered comprehensive of all forms of structure coming within their scope.

I claim:

5 1. A device of the class described comprising, a drawer, a bottomless support comprising a top horizontal member and two vertical side members embracing the upper part of said drawer and entirely out of contact therewith, track means on the sides of said drawer near the upper part 10 thereof having opposite inclined surfaces, rollers on the vertical members of said support traversably engaging said track surfaces and spring pressed means coacting between the drawer and support acting to thrust the rollers and track surfaces into engagement.

15 2. The elements of claim 1 in which said rollers having peripheral surfaces beveled to correspond with the inclined track surfaces which they engage.

20 3. The elements of claim 1 in which said spring pressed means comprises tracks near the longitudinal edges of said drawer and spring pressed rollers mounted on said support and traversing said tracks.

25 CORNELIUS HENDRICKS.
